UNITED STATES PATENT OFFICE.

EDWIN ARCHER HALSETH, OF CLEARBROOK, MINNESOTA, ASSIGNOR OF ONE-FOURTH
TO EDD BOE, OF CLEARBROOK, MINNESOTA, AND ONE-FOURTH TO OTTO LOUIS
HALSETH, OF BAGLEY, MINNESOTA.

SLEIGH.

1,405,779.

Specification of Letters Patent.

Patented Feb. 7, 1922.

Application filed October 12, 1920. Serial No. 416,396.

To all whom it may concern:

Be it known that I, EDWIN ARCHER HALSETH, a citizen of the United States, and resident of Clearbrook, in the county of Clearwater and State of Minnesota, have invented a new and Improved Sleigh, of which the following is a full, clear, and exact description.

In connection with sleighs, it is a well appreciated fact that it has been customary to provide two pairs, or a single pair of runners under the body of the vehicle so that the same might readily move over ice, snow, etc.

These runners are provided in what is commonly known as a "wide gage" or a "narrow gage." The difference in these two types consists of what the terms implies, and upon a customer purchasing either one or the other type, he chooses the same according to the use to which the sleigh is to be put, and the conditions existent in connection with this use.

It is however, often found subsequent to the purchase of a sleigh, that it might be desirable, assuming a narrow gage sleigh has been purchased, to have a wide gage sleigh, or vice versa. Upon these conditions arising, it is of course necessary that the purchaser have all of the parts altered, or a new set of beams and rollers installed to meet the new condition.

Having these defects in mind, I have now constructed a box-sleigh in which the parts are so arranged and constructed as to be capable of adjustment, thus permitting a change from a narrow gage sleigh into a wide gage sleigh, or vice versa.

Reference is had to the attached sheets of drawings as illustrating one practical embodiment of my invention, and in which—

Figure 1 is a side view of a sleigh constructed in accordance with my invention.

Figure 2 is a partly sectional view taken along the line 2—2 of Figure 1 and showing the front beam with runners attached.

Figure 3 is a sectional side view with the runners detached.

Figure 4 is an enlarged sectional top view.

Figure 5 is a partly sectional front view of the front roller.

Figure 6 is a sectional side view taken along the line 6—6 of Figure 7.

Figure 7 is a sectional side view taken along the line 7—7 of Figure 5.

Figure 8 is a sectional plan view of the rear beam and taken along the line 8—8 of Figure 9; and

Figure 9 is a sectional side view taken along the line of 9—9 of Figure 8.

In these views the reference numeral 10 indicates the body of a sleigh which may be of any desirable type, and which is provided with the conventional beam supports 11, through and below which any convenient type of beam pin 12 extends.

Referring now more particularly to the forward beam and its associated parts illustrated in Figures 2, 3 and 4, it will be seen, in accordance with my invention, that the same is constructed of two half-sections 13 and 14 respectively. These half-sections are preferably of some suitable type of metal, and may each mount adjacent their outer ends, runners 15 of any suitable type, secured in any approved manner.

The inner ends of the half-sections are formed so as to provide a socket portion 16 and a projecting portion 17 respectively, adapted to extend one into the other, so as to form a telescoping action, rendering the beam longitudinally extensible. With a view of guiding the half-sections so that no misalignment of the same may occur, one of the same is conveniently formed with a cut-out slot 18, into which a pin 19, secured to the opposite half-section projects, thus providing a guide, and at the same time preventing an extreme extension of the beam by virtue of the fact that the pin 19 co-operating with the outer end of the slot 18, will act as a stop to preclude any possibility of this occurring.

It is now to be noted that both the socket and projecting ends of the beam sections are provided with openings 20, the beam sections being capable of movement one with respect to the other to bring these openings into alignment. Upon the proper adjustment i.e. length of the beam, having been reached, and the openings of the respective inner ends of the sections aligning, the beam pin may be introduced into these openings so that the same projects beyond the lower face of the beam as has been indicated in Figure 2, at which position, a cotter pin or other suit-

able element 21 is utilized to retain the beam in applied position.

The forward roller, illustrated in Figures 5, 6 and 7 embodies a construction similar to that of the beam aforescribed in that the roller comprises two half-sections 22 and 23 respectively, formed with a socket 24 and projecting portion 25 adapted to lie in the socket, together with a series of openings 26 capable of being brought into alignment to retain the longitudinal adjustment desired by inserting a bolt such as 27 through the openings. The draw bar 28 is conveniently associated with forward roller by virtue of being attached to the socket portion 24 of the same.

Finally with reference to the structure illustrated in Figures 8 and 9, depicting the rear roller, it will be appreciated that this 20 roller embodies construction similar in all respects to that illustrated in Figures 5, 6 and 7, with the exception that the draw bar 28 is eliminated.

Also it will be appreciated that the beams 25 may be provided with re-inforcing portions serving to generally strengthen the entire structure, and that the forward beam is conveniently formed with openings 29, or other suitable means permitting of the association of chains 30 with the pairs of runners, whereby the vehicle is provided in the usual manner, with means affording a short turning radius.

Thus I have provided a sleigh which may 35 instantly be converted into a wide, narrow or intermediate gage sleigh, the parts being extremely rigid in construction and economical in manufacture.

Although I have described my invention 40 as applied to a sleigh, it will be obvious that

the beams and associated parts shown and described in the foregoing specification and drawings, may readily be utilized, as bridge beams, in any type of vehicle such as a wagon, without in the least departing from 45 the scope of my invention.

Obviously numerous modifications of structure might readily be resorted to without departing from the spirit of my invention which I claim as,

1. A sleigh including pairs of runners, a beam including a pair of half sections, the inner ends of said sections being formed to provide a socket and projecting portion adapted to extend in said socket respectively, 55 the outer ends of said beams being connected one to each of said runners, said socket and projecting portion being formed with openings adapted to be brought into alignment one with each other, the beam pin of said 60 sleigh being adapted to extend through said openings for retaining the whole in applied position and acting as a swivel for said beam.

2. A sleigh including a pair of runners, a 65 beam extending between said runners, said beam including a pair of sections, the inner end of one of said sections being square, the inner end of said second section providing a square socket for the reception of the 70 inner end of said first named section, the inner ends of both of said sections being formed with openings adapted to be brought into alignment with each other, the beam pin of said sleigh being adapted to extend 75 through said openings for retaining the same in applied position, and acting as a swivel for said beam.

EDWIN ARCHER HALSETH.
